SWITCH ACTUATOR FOR PORTABLE
HAND TOOLSCharles Henry Gubbins, London, England, as-
signor to Wolf Electric Tools Limited, London,
England, a British companyApplication May 24, 1950, Serial No. 163,876
In Great Britain March 31, 1950

2 Claims. (Cl. 200—157)

1

The invention relates to portable hand tools of the kind in which a shaft carrying, or adapted to carry, an implement such as a drill, reamer, box-spanner or grinding wheel, is driven from an electric motor which forms part of the tool and to which the flow of current is controlled by a switch actuated by a trigger which, in turn, is operated by a finger of the user of the tool.

In tools of this type as hitherto constructed, the trigger is normally held in "off" position by means of a spring, and to avoid constant pressure on the trigger when the tool is in use it is customary to provide a detent or plunger which is mounted on a convenient part of the casing of the tool and engages by spring pressure, or can be engaged, in a hole or recess in the trigger when the latter is in its "on" position. This arrangement has the disadvantage that, when it is desired to restore the trigger to its inoperative position for cutting off the supply of current to the motor, it is first necessary to release the detent or plunger. Thus with one hand holding the tool, the operator has to use his other hand to release the trigger and this is an inconvenience, especially where the user needs the other hand for steadyng the work or tool.

The object of the present invention is to provide a trigger arrangement of such a nature that the trigger, when moved to "on" position will automatically be retained in that position, but can be released for movement to "off" position merely by the expedient of manipulating the trigger itself. Hence, by means of the invention, the need for providing a detent or plunger or such-like accessory for holding the trigger in "on" position is dispensed with and the user need use only one hand for holding the tool and operating the trigger under all conditions.

According to the invention, in a portable hand tool of the kind referred to, the trigger is mounted in a guideway for bodily movement from "off" to "on" position against the pressure of a spring, the guideway being provided with a recess in which a projection on the trigger engages as the result of pressure on the trigger from the said spring when the trigger is moved to its "on" position, the arrangement being such that, when the trigger is moved in a direction which is angular to its normal direction of movement, the said projection will be disengaged from the said recess, whereupon the spring will act to restore the trigger to its "off" position.

The invention will now be described in greater detail with reference to the accompanying drawings, in which:

2

Figure 1 is a longitudinal sectional view of a typical construction of portable hand tool with the improved trigger arrangement applied thereto;

5 Figure 2 is a front end view of the tool;
Figure 3 is a rear end view, partly in section, of the tool;

10 Figure 4 is a side elevational view, partly in section, of the rearward part of the tool, showing the trigger in its "off" position;
Figure 5 is a view similar to that of Figure 4, showing the trigger in its "on" position, and

15 Figure 6 is a perspective view illustrating part of the switch mechanism.

Figure 1 is a longitudinal sectional view of a typical construction of portable hand tool with the improved trigger arrangement applied thereto;

20 Figure 2 is a front end view of the tool;
Figure 3 is a rear end view, partly in section, of the tool;

25 Figure 4 is a side elevational view, partly in section, of the rearward part of the tool, showing the trigger in its "off" position;
Figure 5 is a view similar to that of Figure 4, showing the trigger in its "on" position, and

30 Figure 6 is a perspective view illustrating part of the switch mechanism.

The tool illustrated comprises a casing made up of a main body part 1, a front cover plate 2 and a rear cover plate 3, the three parts being secured together by screws 4. The casing accommodates an electric motor having a field winding

35 5 and a rotor 6 (Figure 1). The shaft 7 of the rotor drives, through toothed wheels 8 and 9, a spindle 10 which projects through the end cap 2 and is fitted with a chuck 11 for holding a drill or other implement (not shown).

25 The lower portion of the main body part 1 of the casing is designed to form a trigger-guard 12 and part of a hollow hand-grip 13 the remaining part of which is formed by the lower part of the cover cap 3. The hollow hand-grip accommodates switch mechanism comprising a block 14 of electrical insulating material which is secured in position by one of the screws 4 and is formed with an upwardly extending rear wall 14a joined by side walls 14b. The block 14 is fitted with two spaced contact blades 15 to which electric leads 16 from a flexible cable 17 and to the motor 5, 6, are connected by means of terminal screws 18, the cable passing out through a hole in the base of the hand-grip 13 and being adapted for connection to a source of electric current. The cable 17 includes a safety earth lead 19 which is connected to the base of the hand-grip by a terminal screw 20 so as to protect the user of the tool against electric shock in the event of a short circuit.

30 A tumbler 21 is arranged between the side walls 14b of the block 14 and consists of a block of electrical insulating material fitted with bifurcated contact blades 22, the tumbler being mounted for a rocking movement by the provision thereon of laterally projecting pins 23 engaging in slots 24 in the side walls 14b of the block 14. When the tumbler is rocked in a clockwise direction the contact blades 22 thereon will engage with the 35 contact blades 15 on the block 14, thereby closing

the circuit to the electric motor 5, 6. When the tumbler is rocked in an anti-clockwise direction, the blades 22 will be moved out of engagement with the blades 15 to open the circuit.

The tumbler 21 is actuated by a trigger 25 in the construction and arrangement of which the present invention is characterised, as will now be described.

The main body part 1 of the casing of the tool is formed with a web 26 which extends rearwardly and lies at a distance above the trigger-guard 12, the trigger 25 being arranged in the space between the web 26 and trigger-guard 12 and having a concave forward edge 25a for engagement by a finger of the user, leaving the trigger with an overhanging and forwardly projecting upper part 25b.

The internal edge of the trigger-guard 12 is recessed downwardly to provide a shoulder 27 followed by a rearwardly extending plain face 28, while the under surface of the web 26 is recessed upwardly to provide a shoulder 29 followed by a rearwardly extending plain face 30 lying in parallelism with the face 28. The lower edge of the trigger is formed with a projection 31, the depth of the trigger when measured between its upper edge and the lower edge of the said projection being such that the trigger, when in its forward (inoperative) position, has a snug sliding fit between the plain faces 28 and 30 which thereby constitute a guideway for the trigger.

At the rearward end of the plain face 28, the material of the main body part 1 of the casing is downwardly stepped to provide a recess having a shoulder 32 followed by a rearwardly extending plain face 33. With this arrangement, the distance between the plain face 33 and the plain face 30 of the web 26 will be noticeably greater than the depth of the trigger when measured as previously directed.

The rearward part of the trigger 25 is formed with a recess 34 in which is arranged a sliding sleeve 35 carrying a ball 36 which projects partly out of the sleeve and bears against the upper edge of the tumbler 21, the ball being maintained in resilient engagement with the said edge by means of a compression spring 37 acting between the ball and the inner end of the recess 34. The ball 36 is so located relatively to the length of the tumbler 21, that when the trigger 25 is in its forward (inoperative) position, the ball will lie to the left of a vertical line passing through the axis of the tumbler pins 23, thereby maintaining the tumbler in "off" position as depicted in Figures 1 and 4. When the trigger is moved rearwardly the ball will roll along the upper edge of the tumbler and, in so doing, will cause the tumbler to rock in a clockwise direction, thereby bringing the contact blades 22 into circuit-closing engagement with the contact blades 15, as depicted in Figure 5. When, as depicted in the same figure, the trigger has reached the limit of its rearward movement, the ball 36 will lie to the right of the vertical line passing through the axis of the tumbler pins 23, thereby maintaining the tumbler in "on" position so long as the trigger remains in its rearward position.

When the trigger is in inoperative position, the limit of its forward movement is determined by engagement of the free end of the overhanging part 25b thereof with the shoulder 29 on the web 26 and by engagement of the forward edge of the projection 31 with the shoulder 27 on the

trigger-guard 12. The trigger is normally maintained in this position by a compression spring 38 acting between the rear end of the trigger and the end wall 14a of the block 14, the spring being located by a nipple 39 on the trigger and a slot 40 in the said wall. The spring 38 applies pressure to the trigger along a line above the longitudinal centre-line of the trigger, the spring thus tending also to cant the trigger in an anti-clockwise direction.

When the trigger 25 is pulled backwardly from its initial inoperative position against the pressure of the spring 38, for the purpose of rocking the tumbler 21 into "on" position, the trigger will first move with a simple rectilinear movement owing to the guiding effect afforded by the plain faces 28 and 30. When the trigger has been pulled so far back as to bring the ball 36 to the rear of the vertical centre-line through the axis of the tumbler pins (thereby bringing the tumbler into "on" position), the projection 31 on the trigger will leave the plain face 28 and be brought opposite the recess defined by the shoulder 32 and plain face 33 on the main body part 1. As the spring 38 applies its pressure to the upper part of the trigger, the latter will, as a result, be canted in an anti-clockwise direction, thereby causing the forward edge of the projection 31 to engage with the shoulder 27, as depicted in Figure 5. The trigger will thus be locked in "on" position and will remain in that position for so long as is desired without the need for maintaining finger-pressure on the trigger.

When it is desired to release the trigger for the purpose of bringing the tumbler to "off" position, it suffices merely to apply an upwardly directed pressure, by means of the trigger-finger, to the overhanging part 25b of the trigger. The trigger will thus be canted in a clockwise direction so as to bring the forward end of the projection 31 out of engagement with the shoulder 27, and the spring 38 will then act to drive the trigger forwardly along the guideway 28, 30 into its initial inoperative position.

The trigger arrangement of the invention is of simple construction and is efficient in operation. Once the trigger has been moved into "on" position by simple finger pressure it will be retained automatically in that position without continued pressure from the finger. The same finger is used to release the trigger, when desired, in the manner already described. Release of the trigger can be effected instantaneously by pressure from a finger of the hand used for gripping the tool, while leaving the other hand of the user free. This is of importance where the other hand is required for steadyng the work or tool and the user desires a rapid switch-off at a particular moment.

I claim:

1. In a portable hand tool comprising a casing, a spindle projecting from said casing and adapted to carry a working implement and an electric motor mounted within said casing and adapted to drive said spindle, the provision of a switch to control the flow of current to said motor, said switch comprising a pair of parallel guiding frames formed on said casing, a trigger mounted between said guiding faces to control said switch, a spring acting on said trigger, primarily to maintain said trigger in the position corresponding to the "off" position of the switch, one of said guiding faces formed with a recess and the trigger formed with a projection the arrangement being such that when the trigger is moved to the position corresponding to the "on" position of the

switch the recess and the projection will be brought into register and the spring will tend to cant the trigger to engage said projection and recess for the purpose of retaining the switch in the "on" position until the trigger is canted in the opposite direction when the projection will be disengaged from the recess whereupon the spring will tend to return the trigger to the position corresponding to the "off" position of the switch.

2. A switch according to claim 1, wherein said switch is contained within a hollow hand-grip formed in the casing and the trigger is arranged in the locality of said hand-grip, the trigger being formed with an overhanging part which, when said trigger is retained in the position corresponding to the "on" position of the switch, is adapted to be moved in a direction at right angles to the normal movements of the trigger to cause

disengagement of the projection from the recess so that the spring may then urge the trigger towards its "off" position.

CHARLES HENRY GUBBINS.
